UNITED STATES PATENT OFFICE.

PAUL A. MEEHAN, OF NEW CASTLE, PENNSYLVANIA, ASSIGNEE TO AMERICAN DRESSLER TUNNEL KILNS, INC., OF NEW YORK, N. Y., A CORPORATION OF NEW YORK.

CAR-MOVER FOR TUNNEL-KILNS.

1,326,940.

Specification of Letters Patent.

Patented Jan. 6, 1920.

Application filed October 29, 1918. Serial No. 331,352.

To all whom it may concern:

Be it known that I, PAUL A. MEEHAN, citizen of the United States, and resident of New Castle, in the county of Lawrence and State of Pennsylvania, have invented certain new and useful Improvements in Car-Movers for Tunnel-Kilns, of which the following is a specification.

My present invention relates to tunnel kilns of the type in which the goods to be treated by the kiln are mounted on trucks or cars a train of which normally fills the kiln or the body portion thereof and this train is periodically advanced a car length at a time as fresh cars are inserted one after another at the entrance end of the kiln, by some sort of car pushing mechanism which ordinarily engages the rear car of the train. In kilns of this character it is frequently necessary to advance the forward car of the train to separate it from the main train of cars behind it and by means of which it has been brought into its forward position. For example, in many tunnel kilns the forward goods carrying car of the train must be separated from the body of the train at the exit end of the kiln in order to remove this forward car from the main stationary track in the kiln onto a movable track mounted on a transfer or turn table preparatory to moving the forward car laterally away from the kiln. Where the kiln has, at its exit end, an exit chamber with an egress door from this chamber to the external atmosphere, and a second door between the chamber and the body of the kiln so as to provide an air lock permitting the removal of cars without establishing free communication at any time between the body of the kiln and the external atmosphere, it is necessary to advance the forward car and separate it from the body of the train of cars in order to permit the closure of the door between the exit chamber and the body of the kiln after the forward car has been moved into the exit chamber.

The general object of my present invention is to provide simple and effective means for separating a forward car from the following cars of the train moving through the tunnel kiln when conditions such as

those specified above make this desirable. A specific object of the invention is to provide car advancing means of the character described which may be operated manually by workmen outside of the kiln or by power mechanism located outside of the kiln without permitting any influx of air into the kiln or the escape of the kiln atmosphere to the external atmosphere. Advantageously I may provide means actuated by the movement of the cars for indicating when the car advancing means should be operated and where the car advancing means are power actuated, I may provide automatic means for setting the car advancing means into operation and for stopping its operation whenever the movement of the cars makes this desirable.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described various embodiments of my invention.

Of the drawings:

Figure 1 is a diagrammatic representation of a typical kiln arrangement in which my invention may be employed.

Fig. 2 is a sectional plan of a portion of the apparatus shown in Fig. 1.

Fig. 3 is an elevation, partly in section, of a portion of the apparatus shown in Fig. 1.

Fig. 4 is a view taken similarly to Fig. 3 illustrating a modification.

Fig. 5 is a plan view illustrating a detail of construction employed in Fig. 4.

Fig. 6 is a view taken similarly to Fig. 2 illustrating a modification.

Fig. 7 is an elevation of a portion of the apparatus shown in Fig. 6.

Fig. 8 is a view taken similarly to Fig. 7 illustrating another modification and

Fig. 9 is a view also taken similarly to Fig. 7 illustrating still another modification.

In the conventional kiln representation of Fig. 1 A represents the kiln proper and

B the stationary track rails therein. A vertically movable door *d* separates the kiln proper at its entrance end from an antechamber and *e* represents a vertical movable entrance door at the side of the antechamber. A transfer table *f* movable along the track *G* brings the goods carrying cars *C* from the return track *I* into the antechamber of the kiln, when the entrance door *e* is open. A pusher *h* comprising a hydraulic cylinder or other motor of known type is employed to move the cars *C* successively introduced into the antechamber, off the transfer table and into the body of the kiln and to thereby push forward the train of cars *C* normally filling the body of the kiln a car length each time a car is brought into the antechamber and the device *H* is set into operation. The device *H* comprises a 10 pusher rod *H*¹ proper passing through a suitable stuffing box in the end wall of the antechamber at the forward or exit end of the kiln. At the forward end of the kiln there is an exit chamber separated from the 15 body of the kiln by a vertically movable door *D* and provided with a lateral outlet door *E*. The forward car in the train of cars in the body of the kiln is periodically moved past the door *D* with the latter in 20 its open position onto a transfer table *F* after which the door *D* is closed and the door *E* opened and the transfer table then moved along the track rails *G* to bring the car into the position from which it may be 25 moved off the transfer table onto the return track *I*. Subsequently the turn table *F* is returned to the exit chamber, the door *E* is closed and the door *D* is opened so that the then forward car in the train may be 30 moved onto the transfer table.

The mechanism provided in accordance with the present invention as shown in Figs. 1, 2 and 3 for separating the forward car *C* from the train of cars *C* filling the body of the kiln and advancing this forward car to center it on the transfer table *F*, comprises a reciprocating element *K* passing through a stuffing box or bearing *A*¹ in the end wall of the kiln. The bar *K* is formed 45 at its inner end with a hook *K*¹ adapted to engage the rear side of a lug *C*¹ formed on the under side of the car body when the hook is raised as shown in Fig. 2. The bar *K* may be rotated however to turn the hook into a horizontal position and thereby 50 to permit the passage of the hook beneath the lug *C*¹ preparatory to engaging the latter. To rotate the bar *K* the latter is provided externally of the kiln with an operating handle *K*². To reciprocate the bar *K* the latter is swiveled to a reciprocating element in the shape of a rack bar *K*² forming a part of a jack *L* shown as comprising 55 gearing and a crank arm *L*¹ for manual actuation.

The operation of the car advancing means shown in Figs. 1, 2 and 3 will be readily apparent from the foregoing description. With the transfer table *F* in place in the exit chamber and with the door *D* open and the door *E* closed, the forward car *C* of the train of cars is brought into the position shown in Fig. 2 in which it is partly on the transfer table *F* and partly on the stationary kiln rails *B*. The bar *K* is then manipulated to bring the hook *K*¹ back of the lug *C*¹ of the forward car as shown in Fig. 2. The device *L* is then operated to retract the bar *K* and thereby advance the car *C* engaged by the hook *K*¹ until the then front wheels 80 of the car engage the stops *F*¹ on the transfer table *F*. The door *D* is then closed. The apparatus in this stage is illustrated in Fig. 2. The door *E* is next opened and the transfer table *F* is moved to bring the 85 car resting on it into an alignment with the transfer rails *I* and the car is moved onto the latter. Thereafter the transfer table *F* is returned to its position in the exit chamber, the door *E* is closed, and the door *D* is 90 opened whereupon the apparatus is in position for a repetition of the operation of advancing and removing from the kiln the then forward car of the train.

To avoid the necessity of the manual rotation of the bar *K* to permit the hook *K*¹ to pass under the lug *C*¹ and its subsequent engagement with the lug *C*¹, I may employ the automatically adjustable hook *M* shown in Figs. 4 and 5. In this construction the operating bar *KA* passing through the front wall of the kiln may be regarded as a non-rotatable extension of the bar *K*² of the apparatus shown in Figs. 1, 2 and 3. The hook member *M* is in the form of a yoke pivoted 105 to the bar *KA* by the pivot pin *M*¹. The hook *M* is normally gravity held in the position shown in Fig. 4 in which the upper end of its legs are in position to engage the lug *C*¹ on the car *C*. It is prevented from 110 turning in the counter-clockwise direction from this position by the stop lugs *K*⁶ carried by the bar *KA*. The hook *M* is free to turn in the clockwise direction to permit its upper portions to slide under the car lug 115 *C*¹ when the bar *KA* is moved inward to engage a car to be advanced. Advantageously, as shown, the upper portion of the hook is beveled off as indicated at *M*² to facilitate the movement of the hook under the car 120 lug *C*¹.

In the apparatus shown in Figs. 6 and 7, a reciprocating bar *KB* is employed which carries a car lug engaging hook *M* like that shown in Figs. 4 and 5, but in the apparatus shown in Figs. 6 and 7 the bar *KB* is mounted wholly within the exit chamber of the kiln and is a rack bar reciprocated by the rotation in opposite directions of the gear wheel *P* in mesh with the bar and car- 125 130

ried by a rotating shaft P^1 . The latter projects through the side wall of the kiln and is externally gear-connected to a driving motor Q shown as an electrical motor. With this apparatus it is possible to make the operation of the car advancing mechanism purely automatic. For this purpose a switch R is shown in Fig. 6 in position to be actuated by the forward car C of the train of cars as the latter comes into position in which the door D should be opened. The switch R is connected to the automatic controller S for the motor Q and to start the motor Q in operation when thus actuated. A second switch R^1 is actuated by a car C moved into the exit chamber when the latter comes into the position in which the door D may be closed. The switch R^1 is connected to the motor controller S and serves when actuated to stop the motor Q . In the apparatus shown in Figs. 6 and 7 the kiln AA proper differs from the kiln A previously described in having the doors D and E both transverse to the kiln proper, the stationary track rails B extending from the kiln through the antechamber to the exterior of the latter.

The apparatus shown in Fig. 8 differs from that shown in Figs. 6 and 7 in that the shaft P^1 , which may be driven as is the shaft P^1 of Figs. 6 and 7, carries a plurality of arms T . These engage the lugs C^{10} , of successive cars CA , each giving the car engaged by it the necessary advance movement on a quarter rotation of the shaft P^1 .

The apparatus shown in Fig. 9 differs from that shown in Figs. 1, 2 and 3 primarily in that the bar V corresponding generally to the bar K of Figs. 1, 2 and 3 is reciprocated by means of a lever W connected by a link W^1 to a fulcrum block W^2 secured to the end wall of the kiln. The lever W is adapted to engage a collar V^4 carried by the rod. The latter is formed with a handle V^3 by which the bar may be rotated to bring the hook lugs V^1 into and out of the position in which they straddle the car lugs C^1 . A lug V^2 is also provided on the bar V in position to engage inner end of the stuffing box or bushing A^2 through which bar V passes and thus limit the outward movement of the bar V and consequently of a car engaged by the latter.

While in accordance with the provisions of the statutes I have illustrated and described the best forms of my invention, now known to me, it will be apparent to those skilled in the art that changes may be made in the forms of the apparatus disclosed without departing from the spirit of my invention as set forth in the appended claims.

Having now described my invention, what I claim as new and desire to secure by Letters Patent, is:

1. In a tunnel kiln comprising a kiln proper, cars movable therethrough and means at one end of a section of the kiln for pushing successively presented cars and thereby a train of cars in the kiln section forward a car length each time a car is presented, the improvement which consists in means at the opposite end of the kiln section for engaging a forward car of the train and moving it away from the preceding cars comprising a car engaging device in the kiln and externally controlled operating mechanism for said device. 75

2. In a tunnel kiln comprising a kiln proper, cars movable therethrough and means at one end of a section of the kiln for pushing successively presented cars and thereby a train of cars in the kiln section forward a car length each time a car is presented, the improvement which consists in 80 means at the opposite end of the kiln section for engaging a forward car of the train and moving it away from the preceding cars, comprising a car engaging device in the kiln an operating device outside the kiln and a 85 connection between said devices passing through the kiln wall.

3. In a tunnel kiln comprising a kiln chamber, cars movable therethrough and means at the entrance end of a section of said chamber for pushing successively presented cars into the section and thereby advancing a train of cars in the section a car length each time a car is entered in the section and having means at the opposite ends of the kiln 100 section for moving cars leaving the section transversely to their line of movement through the section, the improvement which consists in an operating device within the kiln for engaging a forward car of the train 105 in the section and moving it onto the said transfer means, and externally controlled operating means for said device. 100

4. In a tunnel kiln comprising a kiln chamber and a door serving when closed to 110 separate the kiln chamber into sections, cars movable successively through said kiln sections and means at the end of one section of said chamber remote from said door for pushing successively presented cars into the 115 section and thereby advancing a train of cars in the section a car length each time a car is entered in the section, the improvement which consists in an operating device located in the kiln for periodically engaging the 120 forward car of the train in the first mentioned kiln section and moving it away from preceding cars and past said door to permit the latter to be closed between the car thus advanced and the following cars. 125

5. In a tunnel kiln comprising a kiln chamber and cars movable therethrough, the improvement which consists in means for successively drawing cars out of a kiln section comprising a bar projecting through 130

the kiln wall in longitudinal alinement with
said kiln section and movable transversely
of its length to clear and engage a car, and
movable longitudinally to draw forward the
car engaged by it.

Signed at city of New Castle, in the
county of Lawrence and State of Pennsyl-

vania, this 23rd day of October, A. D.
1919.

PAUL A. MEEHAN.
